ATTORNEY.

UNITED STATES PATENT OFFICE.

JOSEPH SACHS, OF HARTFORD, CONNECTICUT.

INCLOSED ELECTRIC SWITCH AND METHOD OF ASSEMBLING THE SAME.

Original application filed January 28, 1922, Serial No. 532,450. Divided and this application filed
August 23, 1926. Serial No. 131,042.

The invention relates particularly to a switch mechanism wherein the switch proper is inclosed in a protecting casing, ordinarily of sheet metal, and wherein there is provided 5 a cranked operating spindle for the switch rotatably mounted in bearing apertures in the side walls of the casing.

The principal object of the invention is to provide an improved means and an improved 10 method whereby the operating spindle may be readily put into its proper operative position in the casing and then conveniently and effectively held in such position.

15 In the accompanying drawing I have shown two embodiments of the mechanical features of the invention and one way in which my improved method may be practiced. It will be understood, however, that 20 the drawing is intended for illustrative purposes only and is not to be construed as defining or limiting the scope of the invention, the claims forming a part of this specification being relied upon for that purpose.

25 Of the drawing:

Fig. 1 is a front view of an inclosed switch embodying the mechanical features of the invention.

Fig. 2 is a vertical sectional view taken 30 along the line 2—2 of Fig. 1.

Fig. 3 is a right side elevation.

Fig. 4 is an isometric perspective view on a reduced scale showing the initial formation of the casing as shown in its final condition in Figs. 1, 2 and 3. In this view the operating spindle is shown in an intermediate position which it may assume during the assembling operation.

Fig. 5 is a fragmentary side elevation 40 similar to Fig. 3 but showing a different embodiment of the mechanical features of the invention.

I do not limit myself to any one type of switch mechanism, but for purposes of clearly illustrating the invention I have shown 45 one form of switch mechanism which may be used.

The mechanism as shown comprises a base 1 on which are mounted stationary switch 50 contacts 2, 2 and 3, 3. Pivoted to the respective contacts 2, 2 are movable switch members 4, 4 which are adapted to engage the contacts 3, 3 when moved into positions parallel with the base as shown in Fig. 2.

Also mounted on the base are fuse clips 5, 5 and 6, 6 the clips 5, 5 being connected respectively with the switch contacts 2, 2. The said contacts are adapted to receive cartridge fuses 7, 7 which are thus connected in series with the switches.

For inclosing the entire switch and fuse mechanism there is provided a casing 8 having a back wall 9 and side walls 10 and 11. As illustrated, the base 1 is secured directly to the back wall 9 of the casing, but as to this, there may be variation. The casing is provided with a cover 12, preferably hinged to the casing at the bottom. The cover is provided with inward extending flanges 13 which, when the cover is closed, overlap the 70 side and end walls of the casing.

For operating the switch members 4, 4 there is provided an operating spindle 14 comprising two aligned pivot sections 15 and 16 with a crank section 17 between them, the 75 said crank section including crank arms 17^a and 17^b. The length of the crank sections 17 is such that the two side walls 10 and 11 of the casing are closely adjacent the ends of the said crank section. The spindle also 80 comprises a handle 18 at the end of one of the pivot sections such as the section 16. The two side walls 10 and 11 of the casing are provided respectively with bearing apertures 19 and 20 for receiving and approximately fitting the respective pivot sections 15 and 16 of the operating spindle. When the spindle is in place with its pivot sections fitting the said bearing apertures, the handle 18 is on the exterior of the casing as 85

already shown in Figs. 1 and 3. In order that the switch members 4, 4 may be moved by the crank section 17 of the spindle, the said members are provided respectively with plates 21, 21 of insulating material, each 90 plate being provided with a slot or aperture as shown at 22 for receiving the said crank section 17. From the foregoing description it will be obvious that when the handle 18 is turned the switch members 4, 4 are correspondingly moved to be engaged with or disengaged from the stationary switch contacts 3, 3.

In accordance with the present invention I provide a novel and improved means and a 105 novel and improved method whereby the operating spindle may be put in place and held in place as shown in Figs. 1 to 3.

Referring particularly to Fig. 4, it will be observed that there is initially provided in the side wall 11 of the casing a slot 23 which communicates with the bearing aperture 20. 5 This slot is closed at its ends and does not therefore materially weaken the side wall. The slot is shown as being parallel with the back wall of the casing, but it will be understood that this position is not essential. 10 The width of the slot is at least equal to the diameter of the spindle and it will also be understood that the length of the slot must be at least equal to the amount of offset of the crank section 17 of the spindle so as to 15 permit the spindle to be inserted endwise through the slot. During insertion the spindle is moved endwise and in substantial parallelism with itself into its final operative position with the pivot sections 16 and 17 respectively fitting the bearing apertures 19 and 20 and with the handle 18 on the exterior of the casing adjacent the slotted side wall 11.

In accordance with the invention I provide a closure associated with the casing for closing said slot 23 after the spindle is in place, this closure also serving to hold the corresponding pivot section 16 in place in the bearing aperture 20. A further and very important function of the closure is to serve in cooperation with the casing side walls to prevent or limit endwise movement of the spindle. Such movement is prevented by reason of the engagement of the said crank section at its ends with the said closure and with the side walls 10 and 11.

As to the exact form of closure there may be considerable variation and the closure may be formed integrally with the casing or otherwise. However, I prefer and have illustrated a closure which is formed integrally with the side wall 11 of the casing. As shown, particularly in Fig. 4, the slot 23 is formed by slitting the side wall between the edges thereof and by bending a portion thereof adjacent the slit away from the plane of the said side wall so as to form a projecting lip 24 and so as to leave the said slot. After the spindle has been put in place the lip 24 may be bent backward or returned to the plane of the side wall, the lip thus forming a closure for the slot as clearly shown in Fig. 3 and serving to hold the pivot section 16 in place in its bearing aperture as also shown in the same figure. The lip also serves, as already described, to prevent endwise movement of the spindle.

As already stated I do not limit myself to an integrally formed closure for the slot, but when an integrally formed closure is provided there may be some variation as concerns the details thereof. In Fig. 5 I have shown a construction somewhat similar to that shown in Fig. 5, but instead of 65 providing a single lip 24 for forming the

closure, I have provided four separate lips 25, 25, these being arranged on opposite sides of the bearing aperture.

It will be understood that with the construction described, the spindle can be very easily and quickly put in place by a single endwise movement. I entirely avoid the tortuous threading of the spindle through a small bearing aperture, as has been the prior practice. This application constitutes a division of my copending application for electric switches, Serial Number 532,450, filed January 28, 1922, allowed Oct. 6, 1925, and forfeited April 6, 1926. I do not herein broadly claim a slotted side wall for the purpose described nor do I herein broadly claim the method involving the use of a slotted side wall. These subjects matter are set forth and broadly claimed in my copending application for inclosed electric switch and method of assembling the same, Serial Number 131,041, filed on even date herewith.

What I claim is:

1. The combination with a switch comprising stationary contacts and an associated movable member, of a single piece switch operating spindle comprising two aligned pivot sections with an off-set crank section between them operatively connected with the movable switch member and also comprising a handle at the end of one of the said pivot sections, an inclosing casing for the said switch having its opposite side walls closely adjacent the ends of the said crank section of the spindle and having in the respective side walls aligned bearing apertures for receiving and approximately fitting the respective pivot sections of the spindle, the said casing also initially having in one of its side walls a narrow slot communicating with the corresponding bearing aperture and closed at both ends, the said slot having a width and a length sufficient to permit the said spindle to be moved endwise and in substantial parallelism through the slot into its operative position with the pivot sections thereof fitting the respective bearing apertures and with the handle on the exterior of the casing adjacent the slotted side wall, and a closure associated with the casing for closing the said slot and for holding the corresponding pivot section in place in its bearing aperture, the said closure cooperating with the casing side walls to engage the crank section and thereby prevent endwise movement of the spindle.

2. The combination with a switch comprising stationary contacts and an associated movable member, of a single piece switch operating spindle comprising two aligned pivot sections with an off-set crank section between them operatively connected with the movable switch member and also comprising a handle at the end of one of the said pivot sections,

- and an inclosing casing for the said switch having its opposite side walls closely adjacent the ends of the said crank section of the spindle and having in the respective side walls aligned bearing apertures for receiving and approximately fitting the respective pivot sections of the spindle, the said casing also initially having one of its side walls slitted between the edges thereof with the metal adjacent the slit bent away from the plane of the side wall to form a projecting lip and to leave a slot in the said wall closed at both ends and communicating with the corresponding bearing aperture, the said slot having a width and a length sufficient to permit the said spindle to be moved endwise and in substantial parallelism through the slot into its operative position with the pivot sections thereof fitting the respective bearing apertures and with the handle on the exterior of the casing adjacent the slotted side wall, and the said projecting lip being adapted to be returned to the plane of the corresponding side wall after the spindle is in place so as to close the slot and hold the corresponding pivot section in place in its bearing aperture and so as to also cooperate with the other parts of the said side walls to engage the crank section and thereby prevent endwise movement of the spindle.
3. The herein described method of assembling an electric switch inclosing casing and a single piece with operating spindle comprising two aligned pivot sections with a crank section between them and also comprising a handle at the end of one of the said pivot sections, the said method comprising initially forming the casing with aligned bearing apertures in its opposite side walls for receiving and approximately fitting the respective pivot sections of the spindle and with a slot in one of the side walls closed at its ends and communicating with the corresponding bearing aperture and formed by slitting the side wall between the edges thereof and bending a portion of the metal thereof to form a projecting lip, then moving the spindle endwise and in substantial parallelism through the slot into its operative position with the pivot sections thereof fitting the respective bearing apertures and with the handle on the exterior of the casing adjacent the slotted side wall, and finally when the spindle is in position bending the said lip to return it to the plane of the corresponding side wall so as to close the slot and hold the corresponding pivot section in place in its bearing aperture, the said lip also cooperating with the other parts of the side walls to engage the crank section and thereby prevent endwise movement of the spindle.

JOSEPH SACHS.
